BALE CARRIER ATTACHMENT FOR TRACTORS

Norbert R. Borchering, Box 128,
Garnavillo, Iowa 52049

Filed Jan. 23, 1975, Ser. No. 543,349

Term of patent 14 years

Int. Cl. D12—09; D15—03
U.S. Cl. D40—5

FIG. 1

FIG. 2

FIG. 3

FIG. 1 is a top plan view of a bale carrier attachment for tractors;

FIG. 2 is a front elevational view thereof; and

FIG. 3 is a side elevational view thereof.

I claim:

The ornamental design for a bale carrier attachment for tractors, as shown.
